United States Patent Office.

LORAN MINER, OF SAN FRANCISCO, CALIFORNIA.

Letters Patent No. 96,461, dated November 2, 1869.

IMPROVED CARPET-BEATING MACHINE.

The Schedule referred to in these Letters Patent and making part of the same.

To all whom it may concern:

Be it known that I, LORAN MINER, of the city and county of San Francisco, State of California, have invented a Carpet-Beating Machine; and I do hereby declare the following description and accompanying drawings are sufficient to enable any person skilled in the art or science to which it most nearly appertains, to make and use my said invention or improvements, without further invention or experiment.

My invention relates to a novel machine for beating carpets; and

Its object is to clean the fabric, by means of a series of elastic vibrating whips, which are caused to strike it rapidly as it is passed slowly before them, but are not allowed to remain in contact with it after the blow is given.

It further consists in an improved arrangement of the cams and springs, which lift the whips and impel them forward, so that the machine has all the efficiency of hand-cleaning; and finally, the whips are operated by a peculiar device, so that they move from one side to the other, over the surface of the carpet, as it passes, and thus clean every portion of it.

To more fully illustrate my invention, reference is made to the accompanying drawings, and letters marked thereon.

Figure 1 is a front view of the machine.

Figure 2 is a vertical section, taken transversely through fig. 1.

Figures 3 and 4 are enlarged views of parts of the machine.

A A are the uprights of a stout frame, sufficiently separated to admit the largest carpets, and having the rollers B B' revolving between them.

Over these rollers the carpet is passed, being unwound from the lowest roller D, so as to pass under the roller B and upward in front of the whips C, and thence over the roller B', to be wound upon the upper roller D'.

The whips may be formed of any slender elastic rods, of metal or wood, but I prefer to use hickory, similar in shape to ordinary whip-stocks.

These whips extend nearly the whole distance between the two rollers B B', which keep the carpet in position, and so nearly parallel to it that the whole length of the whips strikes the carpet as they fall.

The whips are fastened to arms E, in such a manner that they can be easily removed and replaced if any of them become broken.

A shaft, F, extends across the frame, and supports the arms E, so that they move loosely on it, and can vibrate and also turn from side to side.

In order to keep the arms from sliding along the shaft, a curved notch, a, is made in the shaft F, as shown, at the point where each arm is supported, and

a pin, b, passes through the arm and notch, in such a manner as to allow the necessary motion, but always keeps the arm in place.

Below the shaft F is the cam-shaft G, which is driven by a pulley, H, receiving motion from the driving-pulley I.

The cams J J are firmly fastened to the shaft, and are made broad enough to strike the lower ends of the arms E at all their inclinations from side to side.

In order to give the requisite blow after the cams release the arms, stiff springs, K, are fastened to the back part of the frame, and are connected with the arms in a suitable manner.

I prefer to make the springs of some elastic wood, as ash, fastening them at the bottom, and connecting the upper ends with the arms E by cords or wires, as these give a much stronger blow than any other form, and with very little jar or noise.

In order to clean the whole surface of the carpet, it is necessary that the whips strike every part of it, and to do this, without multiplying whips, or running the carpet through a number of times, I cause the whips to move slowly from side to side, by means of a series of guides, c c e, between which the arms vibrate.

These guides are fastened to a sliding bar, L, which is moved back and forward at right angles to the motion of the carpet, by means of a bent lever, M, and a connecting-rod, N, which is attached to a crank, O, on the wheel P. This wheel may derive its motion directly from the driving-shaft or from the cam-shaft, as shown.

The sliding bar L is supported on a beam, R, which extends the entire length of the machine, and serves to arrest the arms E, so that the whips will give a strong blow by the momentum which they acquire, but their elasticity immediately withdraws them from the carpet, so that they do not drag over and wear it while awaiting the action of the cams to again raise them.

In order to assist in withdrawing the whips after the blow, and also to deaden the sound which would be made by the stroke of the arms against the beam R, it is covered in front by a pad or elastic cushion, S.

A fan, or other form of blower, may be placed at the top of the machine, at the point where the carpet emerges from the dust-room and passes over the roller B', and by its action prevents the dust from following the carpet out of the room.

A series of brooms may also be used, moving from side to side, similarly to the whips, but placed outside of the dust-room.

Having thus described my invention,

What I claim as new, and desire to secure by Letters Patent, is—

1. The series of elastic whips C, attached to the arms E, and operated by the cams J, together with the springs K and the elastic cushion S, substantially as and for the purposes herein described.

2. A carpet-beating machine, constructed with a series of whips, having a motion from side to side, transversely to the direct action of the whips, substantially as herein described.

3. The device, consisting of the guides c c, sliding bar L, bent lever M, connecting-rod N, and crank O, giving a transverse motion to the whips, substantially as herein described.

4. The device, consisting of the shaft F, with the curved groove or notch a and the pin b, passing through the arm, allowing motion in every direction without displacement, substantially as herein described.

In witness whereof, I have hereunto set my hand and seal.

LORAN MINER. [L. S.]
